Inventor:

Amos Patterson

UNITED STATES PATENT OFFICE.

AMOS PATTERSON, OF CENTERVILLE, IOWA.

CLOTHES-POUNDER.

SPECIFICATION forming part of Letters Patent No. 250,386, dated December 6, 1881.

Application filed June 19, 1880. (Model.)

To all whom it may concern:

Be it known that I, AMOS PATTERSON, of Centerville, in the county of Appanoose and State of Iowa, have invented certain new and useful Improvements in Clothes-Pounders; and I do hereby declare that the following is a full, clear, and exact description of the same, reference being had to the accompanying drawings, in which—

10 Figure 1 is a vertical longitudinal sectional view, on line xx in Fig. 2, of a clothes-pounder of my improved construction; and Fig. 2 is a plan view of the same.

15 This invention has relation to clothes-pounders; and it consists in the improvements in the construction of the same, hereinafter fully described, and particularly pointed in the claim.

20 Referring by letter to the drawings, A designates the pounder, which is composed of a number of vertical sheet-metal tubes, B, soldered together in a group, and provided with a centrally-located vertical handle, C.

25 The tubes B are formed from blanks of sheet metal, the end edges being first folded, as shown at D, and the blank then properly bent and the side edges soldered in any suitable manner. This pounder operates to force the water or washing-fluid through clothes as it is pressed upon them, and the current created 30 by manipulating the device passing through the clothes thoroughly and quickly cleanses them.

The device is cheap and simple, and is su-

35 perior to the perforated wooden beaters in many respects. The thinness of the sheet-metal partitions gives more available surface than where the wooden beater is employed, and as the water forced through the clothes does the work, and not the blows of the pounder, a better result is obtained by my construction. 40

I am aware of Patents No. 109,240 to J. W. Norton, and No. 141,082 to E. Saxton, which are designed with an object similar to that of my invention; but my device differs in construction from these patents. In the latter 45 the cylinders or tubes are formed by perforating a solid block of wood to a certain depth, while in my invention sheet-metal tubes simply soldered together and open at the top are used. I claim nothing shown in these patents; 50 but,

Having thus fully described my invention, what I claim as new, and desire to secure by Letters Patent of the United States, is—

55 A clothes-pounder formed simply of a group of vertical sheet-metal tubes or cylinders, B, open at both ends and soldered together, as shown, to form a hexagonal body, and having their end edges, D, folded over so as to present a smooth edge to the clothes, substantially as and for the purpose set forth.

AMOS PATTERSON.
